UNITED STATES PATENT OFFICE.

RICHARD PEALE, OF ST. BENEDICT, PENNSYLVANIA, ASSIGNEE, BY MESNE ASSIGNMENTS, TO REMBRANDT PEALE, W. SANDERS DAVIES, AND WILLIAM S. WALLACE, TRUSTEES.

MINING AND CONVEYING MACHINE.

Application filed December 29, 1919. Serial No. 348,133.

The invention relates to mining machines, and more particularly to mining and conveying machines.

The objects and advantages of the present invention will be set forth in part herein-after, and in part will be obvious herefrom, or may be learned through practice with the invention; the same being realized and attained through the instrumentalities and combinations pointed out in the appended claims.

The invention consists in the novel parts, constructions, arrangements, combinations and improvements herein shown and described.

The accompanying drawings, herein referred to and constituting a part hereof, illustrate one embodiment of the invention, and together with the description serve to explain the principles thereof.

Of the drawings:

Fig. 1 is a plan, with certain parts in section, of a machine embodying the invention;

Fig. 2 is an enlarged end elevation looking at Fig. 1 from the left.

Fig. 3 is a fragmentary plan of the left hand end of Fig. 1 showing parts that were cut out by the section in Fig. 1;

Fig. 4 is a fragmentary detail, on an enlarged scale and with parts in section, of a part of the drive for the bar cutter, these parts being shown also near the center of Fig. 3.

Fig. 5 is a fragmentary detail view, on an enlarged scale, with parts in section, of the top of the cutter bar guides and of the drive for the cutter bar, these parts being shown in plan at the top end of Fig. 3;

Fig. 6 is a fragmentary detail elevation on an enlarged scale, with parts in section, of the translatory driving means for moving the cutter bar bodily, being substantially on line 6—6 of Fig. 3;

Fig. 7 is an elevation, looking at Fig. 1 from the bottom of the view of Fig. 2 from the left, showing the top cutter in position for cutting the top kerf simultaneously with the chain cutters cutting the bottom kerf.

Fig. 8 is a fragmentary elevation corresponding to the central left hand part of Fig. 2, and showing a height adjustment for the top cutter and its bearings;

Fig. 9 is a diagrammatic elevation showing the complete cut is made by the machine in the coal seam;

Fig. 10 is a somewhat diagrammatic top plan looking down on the top of Fig. 9, but showing the machine in position after the bottom kerf is cut and while the top cutter is cutting;

Fig. 11 is a like diagrammatic view showing the machine making simultaneous top and bottom cuts, like as in Fig. 7;

Fig. 12 is a diagrammatic view looking down on the top of Fig. 11 and showing the coal breaking off and being conveyed away by the conveyer;

Fig. 13 is an enlarged fragmentary detail of the telescoping driving shaft for the top cutter;

Fig. 14 is a fragmentary detail of the clamp for the top cutter, showing the same parts as the upper right hand corner of Fig. 5, but showing them in a central horizontal section; and

Fig. 15 is a detail view showing the combined sprocket wheel assembly 4 and 6, and the crown gear 13.

The present invention in certain of its aspects may be regarded as an improvement upon or an addition to the machine of my co-pending application S. N. 302,929 filed June 9, 1919, but in its broader aspects the present invention may be embodied and utilized independently of said machine of my co-pending application.

In the present embodied machine, a kerf cutter cuts its way into the face of the vein, taking with it into the kerf another cutter, which other cutter then cuts a second kerf or a plurality of kerfs designed to further or entirely separate, or to cause the breaking away of, a body of coal from the vein. The second kerf cutter so introduced into the original kerf has translatory movement or travel preferably in three directions, and thereby the two cutters cut the coal free on four sides, so that it usually breaks off at the back, usually along its cleats or cleavage facings, by its own weight. The second kerf cutter is also adapted to return to its original position preparatory to entering the kerf again with the first kerf cutter, which latter is preferably a bottom kerf cutter.

The cooperating kerf cutters are also adapted for simultaneous operation, as when working from a loose end of the vein, one cutter can cut a bottom kerf and the other a practically parallel kerf thereover, thus

severing the body of coal at top and bottom, which will usually cause the coal to break at the back along its cleats, and to fall of its own weight as the kerfs are extended.

5 The machine by performing the two operations just described can first enter the coal vein, or other vein, head on, and then by lateral or sidewise travel, that is, at right angles to such head-on travel, it will have 10 formed and will be working on its own loose end, and can then continue to operate across the face of the work in the manner last described.

15 In entry work, where the machine is always working head on, it effects or accomplishes the complete work of entry driving, cutting a kerf at the bottom, up one side, across the top, and down the other side of the entry. The coal then breaks at the 20 back across the cleats, and falling upon the conveyer is run back and delivered to a car behind. The machine thus remains at the face of the entry and is continuously engaged in excavating or "driving" the entry, and needing very little attendance or 25 supervision.

More in detail and as preferably embodied, a rectangular frame is provided having a chain cutter running thereabout, the 30 frame sliding on the mine floor and the cutter cutting a bottom kerf into which the frame is drawn by suitable mechanism as the cutting progresses. Within the frame is a second cutter, preferably a rotary bar cutter, lying or nested along and within one 35 side of the frame. When the lower kerf has been cut, the second cutter is within the kerf, and is then put into operation to cut a kerf from the bottom kerf upwardly, thence 40 horizontally above the bottom kerf and then downwardly again to the bottom kerf. This will usually cause the body of coal so defined or partly segregated to break on its back cleats and to fall of its own weight. 45 A conveyer is preferably within the frame to receive and to convey away the dislodged coal.

The second kerf cutter already referred to, as embodied, is a rotary bar cutter lying 50 within one side of the frame carrying the bottom kerf cutter chain. This rotary bar cutter is preferably carried upon guides located on the outer end of the cutter frame, the cutter bar extending inwardly therefrom. The mounting for the cutter bar is moved or progressed along these guides, the cutter bar in the meantime rotating at a 55 high speed to cut the kerf.

60 The guides are preferably shaped to guide the cutter bar first upwardly, then horizontally, and then downwardly again toward the bottom kerf. Means are also provided for returning the cutter bar after it has completed its kerf to its original place within 65 the frame. Also, a motor is preferably

located within the frame which drives both the bottom chain kerf cutter, the rotary bar cutter and the conveyer, and also drives the devices for pressing the entire machine to the work as the kerf cutting progresses. 70

Referring now in detail to the exemplary embodiment of the accompanying drawing, my present invention is shown, as already stated, applied to the machine of my co-pending application Ser. No. 302,929, and as 75 embodying the features of invention, constructions, and functions already described, and in addition thereto features, constructions and functions which will be described and explained at a later point herein. 80

As heretofore stated, the illustrated embodiment of my present invention is shown applied to the bottom kerf cutting and conveying machine of my said application Ser. No. 302,929. Describing first certain parts 85 of my said former machine, a frame 1 is provided which preferably serves as the general frame of the machine and also as the support and guideway for a cutter chain, constituting the preferred form of kerf cutting 90 means. The relative dimensions of the machine are immaterial so far as concerns certain features of the invention, but for certain classes of work, such as entry driving or other narrow work, the frame is of a width 95 such that the kerf cutter will under cut the entire width of the work, the machine in such case being driven or fed to the work in the forward direction only. The machine is also proportioned in such case so as to under cut to the most advantageous depth for the particular work or conditions where used. 100

With these considerations in view, there has been represented on the accompanying drawing a frame composed of two halves which may be held in associated relation. One-half, that at the bottom in Fig. 1, consists of the end members 1^a and 1^b, which are tied together with the lengthwise members 1^c and 33: a cross-plate 102 serves as a stiffener, and as an enclosing housing for certain of the operative mechanism. The other portion of the main frame consists of the end members 62 and 1^d, which are held together by the lengthwise sections 62^a and 36: a cross member 63 serves to support certain of the operative elements and to assure rigidity to the frame. In addition thereto, the two sections of the main frame are closed at the bottom by sole plates and at the top by cover plates as will be described hereinafter. These two halves are held together in any suitable manner, for example by latches and by the chain itself as will be described further in detail. 110

As embodied, the cutter chain 2 passes entirely about the exterior of the frame 1, running in a guideway 3 formed in the frame. While the machine requires relatively little 115

- handling or shifting, to facilitate the same, and for shipping it or moving it from one place of operation to another, and especially to so facilitate its handling in thin seams or veins, the frame is preferably made in two sections, which are preferably self contained, and are adapted to rest side by side on the mine bottom, and are fastened together so as to constitute a unit or integral mechanism.
- 10 As so constituted, one section or unit preferably contains the longitudinal conveyer and the other section or unit contains the cross or transverse conveyer and the motor. The placing of the sections side by side and fastening them together automatically connects the mechanisms of the two parts or sections so that they are driven from a common motor.

Referring more in detail to the drawings, the cutter driving means comprises two sprocket wheels 4 and 5, located preferably at the rear corners of the frame 1. These sprockets are horizontally arranged and their teeth 6 are in mesh with the links of the cutter chain 2, and their shafts 7 and 8 respectively, are journaled in bearings in the frame, as shown at 9 and 10 in Figs. 2 and 6.

The embodied form of driving means for the sprocket wheels 4 and 5 comprise connections from a single motor with slip mechanisms included to compensate for sudden variations in load or strain. Referring to the driving mechanism in detail, a pinion 12 is in mesh with a crown gear 13, formed on the underside of an upper integral part of sprocket wheel 4 which construction permits the sprockets 4 and 5 to be driven in opposite directions from a common drive shaft.

40 Pinion 12 is fixed to a shaft 14 journaled in bearings 15, 16 and 17 in one of the frame sections. This shaft 14 is formed with a friction disk drive or connection 18 between its two ends, which may be of usual construction, with a spring 19 coiled about the shaft and working against a collar 20 on the shaft. This spring urges the friction plates of the connection 18 together to establish a driving element. Since the particular form of friction drive is immaterial, it need not be described in greater detail. The drive for the other cutter chain driving sprocket wheel includes a pinion 25 meshing with a crown gear 26 formed on the side of sprocket wheel 5. The pinion 25 is fixed on a shaft 27 which is journaled in bearings 28 and 29 supported on the frame or unit of the sectional frame. A friction disk device 30 is provided in the shaft 27, which may be of usual construction, and having a spring 31 coiled about the shaft and working against a collar 32 on the shaft. This device 30 likewise may be of any form to assure a frictional drive with a possible slip in case of great strain and need not be described in greater detail.

Means are provided as embodied for driving the chain driving sprocket wheels together, when the frame is made in sections, by connecting their shafts to turn together. Shaft 27 is journaled in the inside reach 33 of its section of the frame with a squared end 34 projecting from the frame. Shaft 14 has an enlarged end 35 journaled in the inside reach of its section of the frame, the enlarged end 35 being socketed to receive the squared end 34 of shaft 27 when the two sections of the frame are fastened together side by side.

Means are provided for driving the cutter and the sprocket wheels and their shafts, and as embodied said means comprise a motor 40, having a pinion 41 fixed on its shaft. Pinion 41 meshes with an idler gear 42, journaled on a bearing 39, which idler gear meshes with a gear wheel 43, which gear wheel is loose on the shaft 14. Fixed to the hub of gear wheel 43 is one member 44 of a clutch, the other member 45 of the clutch being splined and longitudinally slidable on shaft 14 in the usual manner. This clutch simultaneously throws in or out both the sprocket wheels 4 and 5, each sprocket wheel having a friction or slip drive between it and the clutch, as already described. By throwing the clutch 44, 45 in or out, the cutter chain 2 may be driven or stopped, while each drive for the chain is protected against sudden strains by the respective slip drives 18 and 30.

Means are provided for feeding the machine to the work, and as embodied power driven devices are utilized to press the cutters against the coal and to slide the machine along the mine bottom as the kerf deepens. For this purpose the machine is moved bodily by two cables, and in the embodied arrangement jacks 46 and 47 are fastened in appropriate locations at the face of the work, and the cables 48 and 49 are made fast thereto and are wound upon drums mounted upon and driven by the machine.

In the present machine, the drums 50 and 51 are driven from the motor 40, which also drives the cutter chain. A shaft 52 is journaled in bearings 53 and 54 fastened rigidly with regard to the machine frame 1, and fixed on this shaft 52 is a gear wheel 55, which gear wheel meshes with the gear wheel 43 on shaft 14. The two winding drums 50 and 51 are fixed to shaft 52 at either end thereof, and the cables from the jacks 46 and 47 are wound upon these drums, respectively. The machine is preferably mounted on a plurality of shoe plates 56, the bottoms of which are round so that the machine will slide readily over the bottom in any direction.

Guiding pulleys 57 and 58 are mounted on the machine frame at suitable points, for directing the pull of the cables on the ma-

chine. As shown, they are arranged to move the machine forwardly, as in entry work or other narrow work. They may be arranged, if desired, to drive or advance the machine sidewise, as might be required at times in breast or room work, or in long wall work, or the like. With this mechanism constructed and arranged as described, the cutter chain and the advancing means for the machine are operated together and simultaneously from the common motor.

Gear wheel 55 is preferably inclosed in a housing 60, which is formed in the top 61 of a casing inclosing the motor, the sprocket wheels and other driving parts. All the operating mechanism is inclosed in this casing to protect it from loose coal, and also from the dust so far as possible. The casing is formed by the top plate 61 fitting on the top edges of the frame, by the shoe plate 56 by the frame members 62, 62^a, by the plate 36 and by a vertical wall 63 between the driving mechanism and the conveyer.

In the embodied form, a transversely arranged conveyer is arranged at the inside or toward the front of the machine as represented in Fig. 10 and corresponding to the right hand side in Fig. 1, and in front of the motor and driving mechanism already described, upon which conveyer the dislodged coal falls and whereby it is passed across in front of the driving mechanism and then, by cooperating conveying means, alongside of the driving mechanism to the rear and to any desired or suitable loading mechanism or devices.

In such embodied mechanism, an endless conveyer 68 runs over an idle roller 70, located at the inner end of the conveyer and journaled in the machine frame. In the multiple unit or sectional machine, this conveyer extends entirely across its section and discharges on to the longitudinal conveyer located in the other unit or section. At its opposite end conveyer 68 passes over a driving roller 69.

In the present embodied form, the shaft 71 of roller 69 is journaled in the machine frame and is driven through a pinion 82 fixed on the shaft. Meshing with pinion 82 is a gear 83 fixed on a shaft 77 journaled in the frame. Preferably interposed in shaft 77 is a friction clutch or slip drive 72. Fixed to the opposite end of shaft 77 is a bevel gear 74, which meshes with a bevel gear 75, which is fixed on the shaft of pinion 96 which pinion is in the driving train for the longitudinal conveyer 86, later to be described. The drive for the cross conveyer 68, as just described, is different from the drive in my copending application S. N. 302,929, the mechanism having been moved in the present embodiment of this machine to make room for the top cutter mechanism.

In Fig. 14 is shown the embodied locking

device for holding the rotating bar cutter 120 against translatory motion. A locking block 120^a is placed between guides 143 and 144, having a bracket portion 120^b about and outside of one of the guide brackets 145. A bolt 120^c is screwed through the bracket 120^b and into the bracket 145, thus holding cutter bar 120 against translatory motion while permitting it to rotate.

As embodied, in the other section of the machine is mounted what may be termed the longitudinal conveyer, which conveys the dislodged coal to the rear, as already indicated. This conveyer 86 at its inner end runs over an idler roller 87, which is journaled in the machine frame, and at its outer end the conveyer runs over a driving roller 88, which is journaled in the machine frame.

The shaft 89 of this driven roller has a squared end 90, extending from the frame 85 plate 33 like the head 34. This squared head 90 fits into a socket in shaft 91 which is journaled in frame plate 36. When the two general frame sections are fitted together, the shafts will couple as shown in Fig. 1. Shaft 91 has preferably a friction or slip drive 92 and is provided with a bearing 94. Fixed to one part of this shaft 91 is a gear wheel 95, which is driven by a pinion 96 mounted on a shaft 97 journaled in bearing 98 and 99. Pinions 96 and shaft 97 are provided with a clutch 100 which connects and disconnects the pinion and shaft, and serves also as the clutch for the cross conveyer as already described. Shaft 97 is shown as a continuation of the shaft of the common motor 40, which in this embodiment drives the entire machine.

Suitable operating levers are provided for the clutches 45, and 100, respectively, which levers project exteriorly from the casing to provide for the control of the clutches during the operation of the machine. The levers may be of the usual kind, are pivoted on the machine frame and have yoked ends straddling the slidale clutch members in the usual manner, but are omitted from the drawing for clearness of showing.

Additional means besides the cutter chain, for holding the sections together are shown as comprising a latch 117, pivoted on one section of the frame, and taking over a lug 118 on the other section of the frame 1, a pin 119 fitting into a hole in the frame to lock the holding means in engagement.

Up to this point and to include 115 the reference numerals are applied, except as hereinbefore noted, to the same or corresponding parts as in my previous application Ser. No. 302,929.

The embodied form of the second kerf cutter comprises a rotary cutter bar 120 which is nested within the frame 1 as shown at the top of Fig. 1 and Fig. 3. This cutter bar, so far as concerns most features of the

invention, may be of any suitable or approved form, the cutter bar rotating about its own center while translatory movement is imparted thereto to make the kerf cut.

5 The cutter bar 120 is provided with teeth 121, and the bar lies within the frame 1, between the frame and the head of conveyer 68, and longitudinally of the frame, in the direction of progress of the machine when 10 making a head on bottom kerf cut.

The supporting bearings 127 and 134 in which the cutter bar 120 is journaled for its own rotary motion are arranged on guides 128 and 143, along which these bearings are moved or slid to impart the translatory motion to the rotating cutter bar. These guides are formed and positioned so that as the bearings travel along the guides, the cutter bar is moved upwardly from the 20 bottom kerf toward the top of the vein, then horizontally across very close to the top of the vein, and parallel thereto and to the previously cut bottom kerf. When the far side of the bottom kerf is just below 25 the cutter bar, the guides and bearings direct its travel downwardly until its kerf joins the bottom kerf or until the coal or mineral therebetween breaks off.

As embodied the shaft 123 of the cutter bar 120 is journaled in a sleeve or bushing 124 having a shoulder 125 thereon. A collar 126 on shaft 123 lies between the bushing 124 and the shouldered end of the cutter bar to take up wear and to prevent endwise play or movement of the cutter bar. A collar 122 is fixed on shaft 123 on the other side of bearing block 127 to prevent any movement or play.

Shaft 123 is journaled in a bearing 127, 40 which rests upon and slides along a guide 128. The guide 128 has a projecting flange 129, the bearing 127 sliding on the top thereof and a roller 130 running on the bottom side thereof. The roller 130 is on a shaft 131, which is mounted in a downwardly extending arm 132 integral with bearing block 127. Thus the bearing block is held firmly and truly to the guiding face of the guide 128.

50 The guide 128, as embodied, is arranged across the machine near its rear end, and rises vertically from close to one side of the frame 1, as best appears from Figs. 1 and 2, and extends vertically for very nearly 55 the height of the vein; then it is curved and has a horizontal reach nearly as wide as the machine, is then curved downwardly and has a vertically and downwardly extending reach, and is fixed also to the frame at this 60 side (right hand side in Fig. 2). This gives the requisite path of translatory travel to the cutter bar to cut the three-sided kerf already described.

The guide 128 is supported upon or preferably integral with its vertically disposed

supporting plate 132. This structure is bolted or otherwise removably and rigidly fastened with regard to the frame 1, so that the machine may be "knocked down" for storage or transportation.

At the end of shaft 123 is the other bearing or journal block 134 for cutter bar 120. Shaft 123 is here journaled in a sleeve or bushing 135 having an end flange 136 at its inner end. Surrounding bushing 135 is 70 a sleeve or bushing 138 having upon its outer end a flange 139. Bushing 138 serves as a bearing and support for bracket 173 and shaft 171, as will be later described. Flange 139 is shouldered into the bearing or journal block 134. On shaft 123 are collars 140 and 141, bearing against the flanges 136 and 139, respectively, to prevent end play of shaft 123 and to take up wear.

Bearing or journal block 134 slides in 80 guide 142, which has a bottom bearing face 143 and a top bearing face 144, connected together by brackets 145. Guide 142 is of the same form as guide 128, and is integral with or supported upon a vertically disposed plate 146. Plate 146 is disposed transversely of the machine at or near its outer end, and is bolted to or otherwise detachably fixed with regard to frame 1, as already 85 described in connection with guide 128 and its supporting plate 132, and as will be described more particularly with regard to Fig. 8 hereafter.

Means for rotating cutter bar 120 during 90 its translatory travel along guides 128 and 143 are provided. As embodied, said means are driven from the general motor 40 which drives the entire machine. In said embodied form, (Figs. 2, 3 and 4) a bevel gear 150 is fixed on shaft 52. Meshing with gear 150 95 is a bevel gear 151, which is fixed on a vertical shaft 152. Shaft 152 is journaled in bearings 153 and 154, the former being stationary with regard to frame 1 and the latter fixed to plate 146. Fixed to shaft 152 100 is a bevel gear 155, its hub resting on the top of bearing 154.

105 Meshing with pinion 155 is a bevel gear 158, fixed on a horizontally disposed shaft 159. Shaft 159 is journaled in a bearing block 160, supported by and fixed to plate 146. Fixed to the other end of shaft 159 110 is a bevel gear 161. Rotatably supported on the bearing block 16 of shaft 159 is a sleeve 162 carrying a bracket 163. Bracket 163 terminates in a bearing or journal block 164.

115 Rotatably supported in bearing block 164 is a sleeve 166, and fixed to sleeve 166 is a bevel gear 170, which meshes with bevel gear 161 on shaft 159. A collar 167, fixed to rotating bushing 164 on the opposite side of the bearing from gear 170, holds the bushing in bearing block 163 while permitting bushing 164 and gear 170 to rotate in the 120 125 130

bearing. Washers 168 and 169 may be used if desired.

Within bushing 164 and gear 170 is a shaft 171, splined to rotate with the gear and bushing but longitudinally slideable therewithin. The other end of shaft 171 (Figs. 2, 3 and 5) is journaled in a bearing 172 fixed to a bracket 173, which is fixed to and supported by a collar 174, loosely journaled on bushing 138. Shaft 171 has two collars 175 and 176 fixed thereto on either side of its bearing 172, whereby shaft 171 is longitudinally fixed but is rotatably journaled in the bearing. Fixed on shaft 171 is a bevel gear 177 with which meshes a bevel gear 178 fixed on shaft 123 of cutter bar 120.

Referring now to the embodied form of means for imparting translatory movement to the rotating cutter bar, a loose collar 185 encircles shaft 123 between flange 125 of sleeve 124 and bearing block 127. Collar 185 is provided with two diametrically separated rings 186 and 187, and fixed to rings 186 and 187 are the two ends of a cable 188. Cable 188 runs over curved shoes 190 and 191 and over guiding pulleys 192 to 198 as may be required. Cable 188 is wound about a drum 200 which is mounted loosely on shaft 8, but may be mounted or connected elsewhere on the machine when found desirable or convenient. Drum 200 is provided with a clutch pin 201 by which it may be made to rotate with shaft 8 when the cutter bar 120 is to be traveled. A similar clutch pin 202 may be provided for reversing the direction of rotation of drum 200 to travel cutter bar 120 back through the kerf when it has been completed.

The manner of operation of the mechanism just described is substantially as follows:—

The machine may be regarded as lying in a bottom kerf and clutch 211 is thrown in and also clutch 201. Motor 40 drives shaft 52, and through clutch 211 and the other connections already described, shaft 171 is rotated and this rotates shaft 123 and cutter bar 120. At the same time the rotation of drum 200, lifts the cutter bar 120 vertically out of the bottom kerf, the rotating bar cutting a kerf vertically upwardly from the bottom kerf as the bar moves upwardly. The bearing blocks 127 and 134 will travel upwardly along the guides 128 and 134, at the left hand in Fig. 2, drawn by cable 188.

Bearing blocks 127 and 134 will pass about the upper left hand curved part, in Fig. 2, of guides 128 and 134, and will then travel along the horizontal top portion of the guides. This causes the cutter bar 120 to cut a horizontal top kerf substantially parallel to the bottom kerf. When the upper right hand turn in the guides in Fig. 2 is reached, the bearing blocks turn and

pass downwardly over the right hand vertical stretch of the guides in Fig. 2. The cutter bar thus cuts at the right hand side a kerf directed downwardly toward, and if necessary connecting with, the right hand end of the bottom kerf. Many kinds of coal will break off before the two kerfs are connected.

The varying distance between the gear 178 and the gear 161 (Figs. 2, 3, 4 and 5) as the cutter bar 120 travels along the guides 128 and 134 is taken care of by shaft 171 sliding longitudinally in the sleeve 166 of bevel gear 170.

In Fig. 7 and in Fig. 11 the traveling cutter 120 is shown at the top of the supporting and guiding frame. In working in the manner shown in Fig. 9 of cutting out a body of coal around all four sides, the cutter 120 has combined rotary and translatory movement, as already set forth in connection with the description of the mechanism; the translatory motion being indicated by the arrows in Figs. 9 and 10.

When working in the manner indicated in Figs. 11 and 12, that is, when cutting the top and bottom kerfs simultaneously, as might be done in long wall work or in working across the face of a room, the cutter 120 is held in fixed position against translatory motion at the top and preferably at or near the front of its guide frame (as shown in Fig. 11), while rotating to effect the cutting of the kerf. The translatory movement in this case is effected by the movement of the entire machine, as shown in Fig. 12.

The cables 48 and 49 are fastened to jacks 110 and 111, and are wound upon the drums 50 and 51, running also about suitably placed pulleys 57, 108 and 109. A guiding rail or cable 112 may be used to keep the machine running in a true path. The machine thus travels forward making the bottom and top kerf cuts simultaneously. As the coal breaks off along its clearances, it drops upon the conveyors and is delivered alongside the machine, on the bottom ready for loading, for conveying it away.

In Fig. 8 the traveling side and top cutter and its guides are shown adjustable for height, together with the driving mechanism for the top cutter. The plate 146 is shown divided transversely, with bolt and slot supports 205, and corresponding adjustments 206 are provided in the guides for the bearings of the side and top cutter 120.

The shaft 152 in this case is slidably splined within the gear 151 to permit the vertical adjustment just described. If desired, the shaft 171 also may be provided with a sliding joint, as shown in Fig. 13. In that figure, the shaft is cut intermediately of its length and provided with a socket 208 within which fits a decreased end 207 of the other part of the shaft. A spline 209 con-

nects the parts of the shaft for rotation while permitting them to slide. A clamping screw 210 is provided to clamp the shaft at the desired length to correspond to the other adjustments described. In many cases the sliding connection of shaft 171 with bevel gear 170 will be found sufficient for this purpose also. Means are provided for connecting and disconnecting the rotary cutter 120 from its drive, as for instance when the machine is cutting a bottom kerf only. For this purpose there is shown a clutch 211 in shaft 152, operated by a clutch lever 212, with a lever or clamp 213 therefor. The invention in its broader aspects is not limited to the specific mechanisms shown and described but departures may be made thereupon within the scope of the accompanying claims without departing from the principles of the invention and without sacrificing its chief advantages.

What I claim is:—

1. A mining machine including in combination a bottom kerf cutter and a cooperating cutter cutting a vertical kerf beginning in the bottom kerf and progressing upwardly and then horizontally above the bottom kerf.

2. A mining machine including in combination a bottom kerf cutter and a cooperating cutter cutting a vertical kerf beginning in the bottom kerf and progressing upwardly and then horizontally above the bottom kerf and then a vertical kerf downwardly toward the bottom kerf.

3. A mining machine including in combination a bottom kerf cutter and a cooperating cutter cutting a vertical kerf beginning in the bottom kerf and progressing upwardly and then horizontally above the bottom kerf and then a vertical kerf downwardly toward the bottom kerf and a common drive operating the cutters either singly or simultaneously.

4. A mining machine including in combination a bottom kerf cutter and a cooperating cutter cutting a vertical kerf and a horizontal kerf above the bottom kerf, a frame for the bottom kerf cutter entering the bottom kerf as it progresses, the vertical cutter nesting within said frame.

5. A mining machine including in combination a bottom kerf cutter and a cooperating cutter cutting a vertical kerf beginning in the bottom kerf and progressing upwardly, a frame for the bottom kerf cutter entering the bottom kerf as it progresses, the vertical cutter nesting within said frame.

6. A mining machine including in combination a bottom kerf cutter and a cooperating cutter cutting a vertical kerf and a horizontal kerf above the bottom kerf, a frame for the bottom kerf cutter entering the bottom kerf as it progresses, the vertical cutter nesting within said frame, and a common

drive operating the cutters either singly or simultaneously.

7. A mining machine including in combination a bottom kerf cutter, means for pressing it into the face of the vein as the kerf is cut, a vertical kerf cutter entering the vein with the bottom kerf cutter and means for causing it then to cut upwardly through the vein from the bottom kerf.

8. A mining machine including in combination a bottom kerf cutter, means for pressing it into the face of the vein as the kerf is cut, a vertical kerf cutter entering the vein with the bottom kerf cutter and means for causing it then to cut upwardly through the vein from the bottom kerf and then to cut horizontally above the bottom kerf.

9. A mining machine including in combination a bottom kerf cutter, means for pressing it into the face of the vein as the kerf is cut, a vertical kerf cutter entering the vein with the bottom kerf cutter and means for causing it then to cut upwardly through the vein from the bottom kerf and then to cut horizontally above the bottom kerf and then to cut downwardly toward the bottom kerf.

10. A mining machine including in combination a bottom kerf cutter, means for pressing it into the face of the vein as the kerf is cut, a vertical kerf cutter entering the vein with the bottom kerf cutter and means for causing it then to cut upwardly through the vein from the bottom kerf and common means driving the cutters simultaneously or separately.

11. A mining machine including in combination a bottom kerf cutter, a frame therefor, means for pressing the cutter and frame into the face of the vein as the kerf is cut, a second cutter within the frame, and means for causing the second cutter to cut an upward kerf after the frame is in the undercut kerf.

12. A mining machine including in combination a bottom kerf cutter, a frame therefor, means for pressing the cutter and frame into the face of the vein as the kerf is cut, a second cutter within the frame, and means for causing the second cutter to cut an upward kerf after the frame is in the undercut kerf and a motor within the frame and connections therefrom for driving both kerf cutters.

13. A mining machine including in combination a bottom kerf cutter and a relatively long cooperating cutter movable into positions parallel to its long axis for cutting a vertical kerf and a horizontal kerf above the bottom kerf, and a conveyer entering the kerf with the bottom kerf cutter to receive the falling coal and to convey it away.

14. A mining machine including in combination a bottom kerf cutter and a rotating

cutter bar movable into positions parallel to its long axis for cutting a vertical kerf and a horizontal kerf above the bottom kerf and then a vertical kerf downwardly toward the bottom kerf and a conveyer entering the kerf cutter to receive the falling coal and to convey it away.

15. A mining machine including in combination a bottom kerf cutter and a cooperating cutter cutting a vertical kerf and a horizontal kerf above the bottom kerf a frame therefor entering the bottom kerf as it progresses, the vertical cutter nesting within said frame, and a conveyer within the frame 10 to receive the falling coal and to convey it away.

16. A mining machine including in combination a bottom kerf cutter, a frame therefor, means for pressing the cutter and frame 20 into the face of the vein as the kerf is cut, a second cutter within the frame, and means for causing the second cutter to cut an upward kerf after the frame is in the undercut kerf, and a conveyer within the frame and 25 entering the bottom kerf to receive the falling coal.

17. A mining machine including in combination a bottom kerf cutter, a frame therefor, means for pressing the cutter and frame 30 into the face of the vein as the kerf is cut, a second cutter within the frame, and means for causing the second cutter to cut an upward kerf after the frame is in the undercut kerf and then a horizontal kerf above the bottom kerf, and a conveyer within the frame and 35 entering the bottom kerf to receive the falling coal.

18. A mining machine including in combination a bottom kerf cutter, a frame therefor, means for pressing the cutter and frame 40 into the face of the vein as the kerf is cut, a second cutter within the frame, and means for causing the second cutter to cut an upward kerf after the frame is in the undercut 45 kerf and then a horizontal kerf above the bottom kerf and then a downward kerf toward the undercut kerf, and a conveyer within the frame and entering the bottom kerf to receive the falling coal.

50 19. A mining machine including in combination a frame, a bottom kerf chain cutter running therein, and a rotary bar cutter within the frame.

20. A mining machine including in combination a frame, a bottom kerf chain cutter 55 running therein, a rotary bar cutter within the frame, and a conveyer with the frame.

21. A mining machine including in combination a frame, a bottom kerf chain cutter 60 running therein, a rotary bar cutter within the frame, and a conveyer within the frame and a motor within the frame for driving the cutters and the conveyer.

22. A mining machine including in combination a frame, adapted to enter the bottom 65

kerf, a bottom kerf chain cutter running therein, and a rotary bar cutter within the frame.

23. A mining machine including in combination a frame adapted to enter the bottom 70 kerf, a bottom kerf chain cutter running therein, a rotary bar cutter within the frame and a conveyer within the frame.

24. A mining machine including in combination a frame adapted to enter the bottom 75 kerf, a bottom kerf chain cutter running therein, a rotary bar cutter within the frame, a conveyer within the frame, and a motor within the frame for driving the cutters and the conveyer.

80 25. A mining machine including in combination a frame adapted to enter the bottom kerf, a bottom kerf cutter running therein, a rotary bar cutter within the frame, and means for rotating the bar cutter and for 85 progressing it upwardly to cut a kerf upwardly from the bottom kerf.

26. A mining machine including in combination a frame adapted to enter the bottom 90 kerf, a bottom kerf cutter running therein, a rotary bar cutter within the frame and means for rotating the bar cutter and for progressing it upwardly to cut a kerf upwardly from the bottom kerf and for then 95 progressing it horizontally to cut a kerf above the bottom kerf.

27. A mining machine including in combination a frame adapted to enter the bottom 100 kerf, a bottom kerf cutter running therein, a rotary bar cutter within the frame, means for rotating the bar cutter and for progressing it upwardly to cut a kerf upwardly 105 from the bottom kerf and a motor within the frame for driving either or both cutters.

28. A mining machine including in combination a frame adapted to enter the bottom 110 kerf, a bottom kerf cutter running therein, a rotary bar cutter within the frame, means for rotating the bar cutter and for progressing it upwardly to cut a kerf upwardly 115 from the bottom kerf, and for then progressing it horizontally to cut a kerf above the bottom kerf and then downwardly toward the bottom kerf and a motor within the 120 frame for driving either or both cutters and said progressing means.

29. A mining machine including in combination a bottom kerf cutter and a cooperating cutter cutting a vertical kerf and a horizontal kerf above the bottom kerf and a frame therefor entering the bottom kerf as it progresses, the vertical cutter nesting within said frame and means for returning the vertical cutter to its place within the 125 frame.

30. A mining machine including in combination a bottom kerf cutter and a cooperating cutter cutting a vertical kerf beginning in the bottom kerf and progressing upwardly a frame therefor entering the bottom kerf 130

as it progresses, the vertical cutter nesting within said frame and means for returning the vertical cutter to its place within the frame.

5 31. A mining machine including in combination a bottom kerf cutter and a cooperating cutter cutting a vertical kerf beginning in the bottom kerf and progressing upwardly and then returning through the kerf it has cut.

10 32. A mining machine including in combination a bottom kerf cutter and a cooperating cutter cutting a vertical kerf beginning in the bottom kerf and progressing upwardly and then horizontally above the bottom kerf and then returning through the kerf it has cut.

15 33. A mining machine including in combination a bottom kerf cutter and a cooperating cutter cutting a vertical kerf beginning in the bottom kerf and progressing upwardly and then horizontally above the bottom kerf and then a vertical kerf downwardly toward the bottom kerf and then returning through the kerf it has cut.

20 34. A mining machine including in combination a bottom kerf cutter, means for pressing it into the face of the vein as the kerf is cut, a vertical kerf cutter entering the vein with the bottom kerf cutter and means for causing it then to cut upwardly through the vein from the bottom kerf, and to return through the kerf it has cut.

25 35. A mining machine including in combination a bottom kerf cutter, a frame therefor, means for pressing the cutter and frame into the face of the vein as the kerf is cut, a second cutter within the frame, and means for causing the second cutter to cut an upward kerf after the frame is in the undercut kerf, and to then return through the kerf it has cut into the frame.

30 36. A mining machine including in combination a frame adapted to enter the bottom kerf, a bottom kerf cutter running therein, a rotary bar cutter within the frame, and means for rotating the bar cutter and for progressing it upwardly to cut a kerf up-

wardly from the bottom kerf and to then return through the kerf it has cut into the frame.

37. A mining machine including in combination a frame adapted to enter the bottom kerf, a bottom kerf cutter running therein, a rotary bar cutter within the frame, and means for rotating the bar cutter and for progressing it upwardly to cut a kerf upwardly from the bottom kerf and for then progressing it horizontally to cut a kerf above the bottom kerf and to then return through the kerf it has cut into the frame.

42 38. A mining machine including in combination a bottom kerf cutting chain, a frame supporting and guiding it and adapted to enter the kerf as it is made, a second kerf cutter supported by the frame and entering the bottom kerf therewith, and means for imparting cutting and translatory movement to said second cutter when in the kerf.

47 39. A mining machine including in combination a bottom kerf cutting chain, a frame supporting and guiding it and adapted to enter the kerf as it is made, a second kerf cutter supported by the frame and entering the bottom kerf therewith, means for imparting cutting and translatory movement to said second cutter when in the kerf and a conveyer within the frame and entering the bottom kerf therewith to receive the falling coal and to convey it away.

52 40. A mining machine including in combination a bottom kerf cutting chain, a frame supporting and guiding it, means for forcing the frame and cutter into the face of the vein, a rotary bar cutter within the frame and entering the bottom kerf therewith, a guide and support for the bar cutter mounted on the outer end of the frame having horizontal and vertical reaches, and means for rotating the bar cutter and for moving it along said guide and support.

In testimony whereof, I have signed my name to this specification.

RICHARD PEALE.
